CLAIM

The ornamental design for a stylus, as shown and described.

DESCRIPTION

FIG. 1 is a top perspective view of a stylus, showing our new design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is an enlarged top view thereof;

FIG. 8 is an enlarged bottom view thereof;

FIG. 9 is its state diagram thereof;

FIG. 10 is its state diagram thereof; and,

FIG. 11 is an enlarged detail view of area 11 in FIG. 3.

The broken lines in the drawings illustrate the portions of the stylus, which form no part of the claimed design.

The dash-dot-dash broken lines encircling the enlarged views are for annotative purposes only and form no part of the claim thereof.
